LAMP SOCKET

Filed May 9, 1925

UNITED STATES PATENT OFFICE.

LEONARD ERIKSON, OF MALDEN, MASSACHUSETTS, ASSIGNOR TO ERIKSON ELECTRIC COMPANY, OF BOSTON, MASSACHUSETTS, A CORPORATION OF MASSACHUSETTS.

LAMP SOCKET.

Application filed May 9, 1925. Serial No. 29,076.

My invention is an improvement on the lamp socket described and claimed in my United States Letters Patent 1,469,038 dated September 25, 1923 and relates to lamp sockets adapted particularly for use in show-case reflectors of the type disclosed in my United States Letters Patent 1,380,368 dated June 7, 1921.

The general object of my invention is to improve and simplify the construction of such lamp sockets, and special objects are to provide a one-piece socket in which the soldering of the electrical conductors to the terminals of the socket is eliminated and in which a spacing device may be employed to hold the socket away from its support so that lamps other than those of the tubular or cylindrical type may be employed, if desired.

With the foregoing objects in view my invention involves a block of insulating material having longitudinal chambers in its outer ends for receiving the threaded metallic tube and spring contact member which engage the cylindrical surface and central terminal of the lamp plug respectively, said block having also two longitudinal recesses between said chambers, each enclosing a metallic bridge member, means such as screws mechanically and electrically connecting the said threaded tubes with one bridge member, other means mechanically and electrically connecting said tubes, and screws or other suitable means engaging the spring contacts and threaded into the other bridge member, together with binding-posts electrically connected with the tops of said bridge members for receiving loops formed in the electrical conductors or else short leads connected to said conductors.

My invention comprises also a flanged spacing device interposed between the socket and the conductor conduit, said device being suitably attached to said conduit and socket, preferably by a screw passing through the former and threaded into a laterally extending lug formed integral with the lower end of one of the walls of said device.

In order to prevent relative movement between the spacing device and socket, the lower surface of the former is provided with lugs arranged to cooperate with recesses in the upper face of said socket.

One embodiment of my invention is shown

in the drawings which accompany and form a part of this specification in which—

Figure 1 is an elevation of my improved lamp socket applied to a showcase reflector;

Fig. 2 is a plan view of the construction shown in Fig. 1 with the reflector removed;

Fig. 3 is a central longitudinal section on an enlarged scale taken on the line 3—3 of Figs. 4 and 5;

Fig. 4 is an end view looking toward the lefthand end of Fig. 3;

Fig. 5 is a transverse section taken on the line 5—5 of Fig. 3;

Fig. 6 is a longitudinal section of a single socket;

Fig. 7 is a plan view of the socket shown in Fig. 3;

Fig. 8 is a horizontal longitudinal section taken on the line 8—8 of Fig. 4.

In the particular drawings selected for more fully disclosing my invention 10 represents a block of insulating material, the outer ends of which are chambered as shown at 11, 12, for receiving the threaded metallic tubes 13, 14 which engage the cylindrical surface of the lamp plug, and also the spring contact members 16, 17 which engage the central terminal of said plug. Arranged midway between said chambers 11, 12 are two longitudinal recesses 18, 19 separated by a central longitudinal partition 20 and housing the bridge members 21, 22, respectively, said bridge members consisting of strips of brass or other conducting material bent to the shape shown, that is, having two vertical portions connected by a horizontal top-piece. Means are provided for mechanically and electrically connecting the threaded tubes 13, 14, with the bridge member 22, and in the present instance such means are shown as screws 23, 24, having their heads engaging the tubes, respectively, and their ends threaded into the vertical portions of said bridge.

By means of the screw 25 passing through a hole in the central portion of the block 10, the threaded tubes are mechanically and electrically connected together, a nut 26 being threaded on said screw and engaging the tube 13.

In order to connect the spring contact members 16, 17 electrically and mechanically to the bridge member 21, any suitable means such as the screws 27, 28 may be employed,

said screws engaging the flat strips 29 integral with said spring contacts and being threaded into the upright portions of said bridge 21. Electrically connected with the tops of said bridge members are binding posts shown in the present instance as screws 30, 31 threaded into the top pieces of said bridges, respectively.

The upper face of the block 10 is provided with four longitudinal slots 32, each being inclined downwardly and terminating at the opposite ends of one of the two recesses 18, 19 to accommodate the electrical conductors when the socket is attached directly to its support without the interposition of the spacing member about to be described.

A portion of the top member of the reflector is shown at 33 and attached to the underside thereof, as by the screws 34, is a conduit 35 for electrical conductors, shown at 36, said conduit consisting of a base and two upwardly inclined side members as described in my Letters Patent above mentioned. Interposed between the base of said conduit and the upper face of the socket is a flanged spacing device 37 shown in the present instance as a hollow rectangular member having oppositely-disposed flanges 38 extending laterally from two of the side walls thereof and threaded to receive the screws 39 whereby said device is attached to the base of the conduit 35 and having on its lower surface a plurality of lugs 40, four in number in the present instance, arranged to fit into the slots 32, respectively, to prevent relative movement between the spacing device and the socket. The flange 41 extends laterally from the lower end of one of the side walls toward the opposite wall and is provided with a threaded hole for receiving the upper end of the screw 42 which passes through the hole 43 in the central portion of the socket for attaching the latter to said spacing device. It will be understood of course that spacing devices of different heights will be employed when lamps of different diameters are used in the sockets. A sheet of insulation 43 preferably is placed between the socket and the spacing member to cover the bridges and their attached binding-posts.

When the spacing members are used, short leads 44 from the conductors 36 pass through perforations 45 in the base of the conduit and are connected electrically to the

binding-posts 30, 31, respectively. When, however, tubular lamps are used and the spacing members are not necessary, a loop is formed in each of said conductors 36 for attachment to said binding-posts, the slots 32 affording space for the passage of said conductors to said binding-posts.

As shown in Fig. 6, my invention may be incorporated in a single socket, in which case the threaded tube 13 and spring contact member 16 are connected, respectively, to the bridge members 22, 21 and the screw 46 and nut 47 mechanically secure said tube to the socket, the construction otherwise being the same as that already described in connection with the double socket shown in Fig. 3.

Having thus described illustrative embodiments of my invention without however limiting the same thereto, what I claim and desire to secure by Letters Patent is:—

1. A spacing device for holding a lamp socket away from its support comprising a hollow rectangular member, oppositely-disposed flanges extending laterally from two of the side walls thereof, lugs on the lower surface of said member arranged to co-operate with recesses in said socket to prevent relative movement between said device and said socket, and a flange extending laterally from the lower end of one of its walls toward the opposite wall for receiving a member adapted to attach said device to said socket.

2. In combination, a lamp socket comprising a block of insulating material provided with a pair of spaced longitudinal recesses in the upper face thereof, said upper face also having two pairs of conductor receiving slots each slot terminating at the opposite ends of said recesses and communicating therewith, a tubular spacing device adapted to hold said socket away from its support, said spacing device being provided with lugs disposed in said slots to prevent relative movement between said socket and said device and means for securing said spacing device to said socket, said means being accessible from the underside of the socket and extending through the socket between the longitudinal recesses.

In testimony whereof, I have hereunto subscribed my name this 8th day of May, 1925.

LEONARD ERIKSON.
